By his attorney, Charles S. Gooding.

UNITED STATES PATENT OFFICE.

AUBREY R. GOODWIN, OF MELROSE, MASSACHUSETTS, ASSIGNOR TO CHELSEA RADIO CO., OF CHELSEA, MASSACHUSETTS, A PARTNERSHIP CONSISTING OF AUBREY R. GOODWIN, CARMINE CATALDO, AND PELLEGRINO RIZZO.

VARIABLE GRID RESISTANCE.

1,420,189.

Specification of Letters Patent. Patented June 20, 1922.

Application filed September 8, 1921. Serial No. 499,173.

To all whom it may concern:

Be it known that I, AUBREY R. GOODWIN, a citizen of the United States, residing at Melrose, in the county of Middlesex and State of Massachusetts, have invented new and useful Improvements in Variable Grid Resistances, of which the following is a specification.

This invention relates to a variable grid resistance.

In radio communication a device known as a "vacuum tube" is universally used to receive, amplify and generate oscillations. This vacuum tube consists of an evacuated glass bulb containing three elements known as the filament, grid and plate.

Metallic bodies when heated to a dull red glow, or higher temperature, throw off negative electrons. When both the plate and grid are at zero potential these negative electrons are propagated by the filament in all directions. If, however, the plate becomes positively electrified the negative electrons are attracted to it and flow in a concentrated stream which is called an electron current. The grid is the controlling member of this stream and is placed between the filament and the plate. If the grid is positively electrified, it aids the passage of the electrons from the filament to the plate, increasing the value of the electron stream. If the grid becomes negatively electrified, it repels the negative electrons, reducing the value of the electron stream, and if the grid becomes sufficiently charged to a negative potential, it may stop the flow of electrons to the plate altogether.

In radio communication, the circuits are so arranged that the incoming oscillations from the antenna act upon the grid, which alternately becomes positively and negatively charged. During the positive charge, however, all of the negative electrons are not removed from the grid, hence the grid during the many succeeding oscillations accumulates a negative charge which is not removed during the positive half of the cycle and materially reduces the flow of the electron stream and it becomes necessary to use some auxiliary means to remove this excess negative potential and hence the use of the grid resistance, which if of the proper value allows the extra negative charge of the grid to leak off and keeps the vacuum

tube in its most sensitive operating condition.

The amount of this negative accumulation on the grid varies with the incandescence of the filament, the positive potential on the plate, the degree of evacuation of the tube and the gas content of the tube. If the tube contains a considerable amount of gas, part of the excess negative charge on the grid will leak to the filament through the gas itself. In very highly evacuated tubes no such leakage can take place and a grid resistance must be employed. To meet these changing conditions in a tube and the different characteristics of different tubes, a fixed value of grid resistance is insufficient to maintain the tube at its proper operating characteristic, and hence I have devised a variable grid resistance, which allows the introduction of the proper leak resistance at will, and hence an immediate and accurate control of the grid potential and the means for always maintaining the vacuum tube at its proper operating characteristic.

The object of the invention is to provide a device by means of which a vacuum tube may always be kept at its most sensitive operating condition.

The invention consists in the combination and arrangement of parts set forth in the following specification and particularly pointed out in the claims thereof.

Referring to the drawings:

Figure 1 is a front elevation of a device embodying my invention.

Fig. 2 is a transverse section taken on the line 2-2, Figure 1.

Fig. 3 is a rear elevation of the device.

Like numerals refer to like parts throughout the several views of the drawings.

In the drawings, 5 represents a base preferably circular in form and constructed of any suitable insulating material, but preferably of material which may be moulded as desired. A recess 6 is formed in the rear side of the base 5. Centrally located upon the base 5 is a switch 7 embodying therein, a contact arm 8 constructed of resilient sheet metal, an operating handle 9 constructed of insulating material and a stud 10 which constitutes a pivot for the switch 7 and is secured to the operating handle 9 by a screw 11 in such manner as to also clamp the contact arm 8 between a shoulder

12 provided upon the stud 10 and the operating handle, whereby said operating handle, stud and contact arm may be rotated in unison. The stud 10 is electrically connected by means of a strip of sheet metal 13 located within the recess 6 with a suitable binding post 14 to which an electric wire 15 may be attached in the usual well-known manner. The stud 10 projects slightly through an opening 16 provided in the strip 15 and the latter springs into contact with a washer 17 secured at the end of the stud 10 by a screw 18.

Mounted upon the base 5 and arranged concentric with the median axial line of the switch 7 are a plurality of studs 19 constituting contacting points. The studs 19 are shouldered at 20 and project into openings 21 provided in the base 5, being clamped to said base by screws 22. Located within the recess 6 and clamped against the under surface of the base 5 by means of the screws 22 is a piece of sheet material 23, upon a portion of the surface of which is a deposit of dried ink 24 which extends in an arc parallel with the center line of the contact studs 19. The sheet material 23 is a non-conductor for electricity. From the curved ink surface 24 radial branches 25 extend beneath each of the screws 22 with the exception of a screw 22^a which has no connection with the ink surface. The ink surface is a conductor for an electric current and constitutes a resistance through which the extra negative charge of a grid previously mentioned may leak.

The ink surface 24 is electrically connected to a strip of sheet metal 26, one end of which is secured beneath a screw 22^b and connects with a suitable binding post 27 to which an electric wire 28 may be attached in the usual well-known manner.

Stop pins 29 and 30 are suitably positioned upon the upper surface of the base 5 in the path of the contact arm 8 and limit the movement of said arm in either direction. Numerals from 0 to 9 are placed upon the outer surface of the casing 5 adjacent to the contact studs 9 and represent different values of grid resistance from one-half million ohms to five million ohms in steps of approximately one-half million ohms. The contact stud which is not connected with the resistance material 24 and which is indicated at 19^a is secured in the base 5 by the screw 22^a. This stud 19^a which is not included in any electric circuit through the device has a numeral 10 located upon the upper surface of the casing 5 adjacent thereto.

In practice the device illustrated may be connected by a shunt to the grid condenser, or as is usually the case, between the grid and the filament. The switch 7 is rotated by means of the operating handle 9 to locate the arm 8 in contact with the stud 19 which

is found will keep the vacuum tube in its most sensitive operating condition. Many vacuum tubes will not function without the aid of a grid resistance and the efficiency of operation is greatly increased by the use of a variable resistance.

Although nine different values of resistance are obtainable with the device illustrated in the drawings, either a smaller or larger number may be used without departing from the spirit of this invention.

It is also evident that while a circular instrument base is illustrated in the drawings, any form of base may be employed and the contact studs which are illustrated positioned in an arc concentric with the median line of the switch may be arranged in a straight line, or other arrangements adaptable to the best operation of the type of switch employed.

The device herewith illustrated and described may be employed in radio communication in connection with transmitting vacuum tubes as well as receiving tubes and irrespective of their functions, whether as detectors, amplifiers or oscillators.

I claim:

1. In combination, a leak resistance material and a switch constructed and arranged to co-operate with said resistance material to produce a plurality of predetermined values of leak resistance.

2. A device of the character described having, in combination, a base constructed of insulating material, a leak resistance material secured to said base, a plurality of electric contact points communicating with said leak resistance material and a switch constructed and arranged to engage said contact points.

3. A device of the character described having, in combination, a circular moulded base of insulating material, a leak resistance material secured to said base, a plurality of studs fast in said base and arranged in an arc concentric with the center of said base, said studs communicating with said leak resistance material and a switch constructed and arranged to engage said studs.

4. A device of the character described having, in combination, a base constructed of insulating material, a layer of insulating material fast to said base, a deposit of leak resistance material upon said insulating material, a plurality of contact studs fast in said base and communicating with said leak resistance material and a switch constructed and arranged to engage said contact studs.

5. A device of the character described having, in combination, a base constructed of insulating material, a layer of insulating material fast to said base, a deposit of dried ink upon said insulating material, a plurality of contact studs fast to said base and communicating with said ink deposit and a

switch constructed and arranged to engage said contact studs.

6. A device of the character described having, in combination, a base constructed of insulating material, a layer of insulating material fast to said base, a deposit of dried ink upon said insulating material, said ink deposit having branches extending therefrom, a plurality of contact studs fast in 5 said base and communicating with the branches of said ink deposit, and a switch 10

constructed and arranged to engage said contact studs to produce a plurality of predetermined values of leak resistance.

In testimony whereof I have hereunto set 15 my hand in presence of two subscribing witnesses.

AUBREY R. GOODWIN.
